United States Patent Office

Des. 194,736
Patented Feb. 26, 1963

194,736

PORTABLE POWER SAW

James H. Godfrey, 113 Westview Terrace, Berlin, Conn.,
and Richard H. Russell, 681 Arch St., New Britain,
Conn.

Filed Sept. 29, 1961, Ser. No. 66,913

Term of patent 14 years

(Cl. D91—3)

Fig. 1

Fig. 4

Fig. 2

Fig. 3

FIG. 1 is a perspective view of a portable power saw showing our new design;

FIG. 2 is a side elevation thereof with the saw blade omitted for convenience of illustration only;

FIG. 3 is a top plan view thereof as shown in FIG. 2; and

FIG. 4 is a reduced bottom plan view thereof as shown in FIG. 2.

We claim:

The ornamental design for a portable power saw, as shown and described.
